UNITED STATES PATENT OFFICE.

ENOS C. KERSEY, OF NEWPORT BEACH, CALIFORNIA.

WAVE-MOTOR.

1,111,656.

Specification of Letters Patent. Patented Sept. 22, 1914.

Application filed November 12, 1913. Serial No. 800,582.

To all whom it may concern:

Be it known that I, ENOS C. KERSEY, a citizen of the United States, residing at Newport Beach, in the county of Orange and State of California, have invented new and useful Improvements in Wave-Motors, of which the following is a specification.

This invention relates to wave motors, the object in view being to provide simple and reliable mechanism for pumping either air or water to a point of storage or use, the machine comprising a buoyant body mounted in such position relative to the sea shore as to be moved upwardly and downwardly by the waves to operate the pumping mechanism, the buoyant body being supported and held in position by means which admit of the free up and down movement thereof, combined with means for shifting the pump mechanism and the buoyant body toward and away from the shore line in accordance with the condition of the tide, the said shifting means also being designed for the purpose of moving the operative parts of the mechanism on shore in case of storms.

With the above and other objects in view, the invention consists in the construction, combination and arrangement of parts, as will hereinafter be more fully described, illustrated and claimed.

In the accompanying drawings:—Figure 1 is a top plan view of a wave motor embodying the present invention. Fig. 2 is a vertical longitudinal section through the same. Fig. 3 is a vertical transverse section through the supporting structure, showing the traveling crane, float and connections in elevation. Fig. 4 is a detail vertical section showing the engagement between the tie bars and stay rails. Fig. 5 is a detail sectional view of one of the springs and its housing used in connection with each flexible stay.

The wave motor contemplated in this invention comprises essentially a supporting structure which as best illustrated in Figs. 2 and 3 consists of parallel rows of piling designated generally at A, the piling being in two parallel series and connected at the top by cap pieces 1 which as shown in Fig. 2 are inclined from the shore line outwardly to enable the crane and float hereinafter particularly described to be shifted in accordance with the height of the tide to obtain the best results from the wave motor as a whole.

Secured to and extending lengthwise of the cap pieces 1 are parallel track rails 2 along which travel the carrying wheels 3 of a traveling crane designated generally by the reference character B, said crane embodying a substantially flat and horizontal platform 4 upon which is mounted a pump the cylinder of which is designated at 5.

Extending parallel to the track rails 2 but at a lower elevation are stay rails 6 one of which is illustrated in detail in Fig. 4 where it is shown as consisting of a pipe although it will be evident that the stay rails need not be tubular but they are preferably round in cross section so as to enable upper and lower grooved rollers 7 and 8 to cooperate therewith and move lengthwise thereof. Tie bars 9 have a jointed connection at 10 with the under side of the platform 4 of the traveling crane and each of said tie bars is provided adjacent to its lower end with a roller bracket 11 on which the rollers 7 and 8 are journaled. The rails 6 constitute stay rails in that, in conjunction with the tie bars 9, they serve to hold the traveling crane on the track rails 2 and prevent any possibility of the crane becoming derailed.

C designates the buoyant member or float which is shown as in the form of an ordinary double ended pontoon or lighter which normally occupies a position directly under the crane B as shown in Figs. 1 and 2. A plurality of flexible stays 12 connect the float C with the tie bars 9 as shown in Figs. 2 and 3, said flexible stays consisting either of ropes, chains or the equivalent thereof. At a point intermediate the ends of each flexible stay, there is a spring 13 which is shown conventionally in the form of a casing containing an involute or helical spring such as is ordinarily employed in tape measures, said spring serving to draw inwardly the opposite ends of the flexible stays 12 so that said stays will automatically lengthen and shorten themselves as the float C rises and falls. The stays 12 serve to hold the float C centrally under the traveling crane so as to insure the proper and continuous operation of the pumping mechanism.

The piston or pump rod 14 extends downwardly through an opening in the platform 4 and is provided intermediate its ends with a universal joint 15 and is also connected by a universal joint 16 to the top of the float C. The universal joints referred to prevent the cramping of the piston or pump rod

while insuring the reciprocatory motion of the pump piston due to the up and down movements of the float C under the influence of the waves.

5 The means for shifting the traveling crane B and the float C is best illustrated in Figs. 1 and 2 wherein it will be observed that at each end of the stationary supporting structure A, anchoring members such as 10 posts or stakes 17 and 18 are provided, the same being equipped with guide pulleys 19 and 20 around which passes a flexible cable 21 attached at its opposite ends to the float C as shown at 22 and 23. The cable 21 passes 15 over the platform 4 of the crane and around a drum 24 which is journaled in supporting brackets 25 on said platform 4 and driven by a motor D, for the purpose of shifting the crane B and the float C toward and away 20 from the shore line in accordance with the height of the tide. 26 designates a service pipe leading off from the pump 5 to a storage tank or reservoir or other point of use.

25 What I claim is:—

1. In a wave motor, a stationary supporting structure, inclined track rails thereon, a traveling crane movable along said rails, a float flexibly connected with said crane 30 and also movable together with said crane lengthwise of said supporting structure, a pump mounted on said crane, and a pump operating connection attached to and actuated by said float.

35 2. In a wave motor, a stationary supporting structure, inclined track rails thereon, a traveling crane movable along said rails, a float flexibly connected with said crane and also movable together with said crane 40 lengthwise of said supporting structure, a pump mounted on said crane, a pump operating connection attached to and actuated by said float, a flexible cable for shifting the

position of said crane and float, and anchoring means for said cable at opposite ends of said supporting structure.

3. In a wave motor, a stationary supporting structure, inclined track rails thereon, a traveling crane movable along said rails, a float flexibly connected with said crane and also movable together with said crane lengthwise of said supporting structure, a pump mounted on said crane, a pump operating connection attached to and actuated by said float, stay rails fastened to said supporting structure parallel to the track rails, tie bars extending downwardly from said crane, and rollers on said tie bars movable along said stay rails.

4. In a wave motor, a stationary supporting structure, inclined track rails thereon, a traveling crane movable along said rails, stay rails parallel to said track rails, tie bars extending downwardly from said crane, rollers on said tie bars movable along the stay rails, a float, flexible stays connecting the float and tie bars, and pumping means carried by said crane and actuated by said float.

5. In a wave motor, a stationary supporting structure, inclined track rails thereon, a traveling crane movable along said rails, stay rails parallel to said track rails, tie bars extending downwardly from said crane, rollers on said tie bars movable along the stay rails, a float, longitudinally extensible stays connecting the float and tie bars, and pumping means carried by said crane and actuated by said float.

In testimony whereof I affix my signature in presence of two witnesses.

ENOS C. KERSEY.
